UNITED STATES PATENT OFFICE.

ALONZO B. CLARK, OF MANSFIELD, OHIO.

WIRE-HANGER.

1,334,228.

Specification of Letters Patent. Patented Mar. 16, 1920.

Application filed September 29, 1919. Serial No. 327,168.

To all whom it may concern:

Be it known that I, ALONZO B. CLARK, a citizen of the United States, residing at Mansfield, in the county of Richland and State of Ohio, have invented new and useful Improvements in Wire-Hangers, of which the following is a specification.

This invention relates to wire supporting devices and has for its object the provision of a clamp whereby a wire or cable of any description may be rigidly supported, the clamping member including relatively movable arms adapted for engagement with the wire, and wedging means for forcing the jaws of the clamping member into close engagement with the wire.

An important and more specific object is the provision of a device of this character in which the clamping jaws have their inner faces inclined for engagement upon an inclined portion of the support proper whereby upon longitudinal movement of the clamping members in one direction with respect to the support proper, the jaws will be urged together.

An additional object is the provision of a device of this character which will be simple and inexpensive in manufacture, highly efficient in its gripping action, durable in service, and a general improvement in the art.

With the above and other objects and advantages in view, the invention consists in the details of construction to be hereininafter more fully described and claimed, and illustrated in the accompanying drawing in which—

Figure 1 is a side elevation of the device,

Fig. 2 is an elevation taken at right angles to Fig. 1, the wire being shown in section,

Fig. 3 is a longitudinal sectional view,

Fig. 4 is a longitudinal sectional view taken at right angles to Fig. 3, and

Fig. 5 is a cross sectional view taken above the retaining ring.

Referring more particularly to the drawings, the numeral 10 designates the relatively stationary support which is formed as an attaching base 11 and a cylindrical shank 12 extending therefrom, having its intermediate portion tapered, as shown at 13, and terminating in a reduced portion 14 having one side cut away, as shown at 15, to provide a shoulder 16.

The relatively movable portion of the device comprises a pair of members 17 which are substantially mating and each of which includes a body 18 having a bored portion 19 conformingly engaging the tapered and reduced portions 13 and 14 of the shank. Each member 17 further includes a laterally widened portion 20 having a groove 21 adapted to engage a wire or cable A to be supported. Secured upon one of the members 17 is a ring member 22 adapted to encirclingly engage the other member 17. Adjacent the ring 22 and between it and the widened ends 20, the members 17 are provided with recesses 23 adapted to register with the cut away portion 15 in the shank.

In the operation of the device the members 17 are both assembled within the ring 22 and are then both slipped partly onto the shank 12, after which the wire A is disposed between the widened portions 20 which constitute the clamping jaws, the wire being engaged within the grooves 21. The clamping members 17 are then moved longitudinally upon the shank whereupon the engagement of the tapered portion 13 of the shank with the correspondingly shaped bore of the members 17 will cause the jaws 20 to grip the wire firmly. In order to effect a still tighter gripping action to retain them, I employ a wedge 24 which is then inserted within the recesses 23 in the members 17 and the cut out portion 15 in the shank and this wedge member is driven in so that the engagement of the edges thereof with the ring 22 and the shoulder 16 will cause the clamping member to be drawn still farther along the shank, thus clamping the wire very rigidly.

From the foregoing description and a study of the drawings it will be apparent that I have thus provided a simply constructed and easily applied support for holding wires or cables, the device being adapted for use in a great many different places where wire or cables are used for different purposes.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention, I claim:

A device of the character described comprising a support including an attaching plate and a shank extending therefrom, said shank being provided intermediate its ends with a tapered portion and terminating in a reduced extension cut away at one side to define a shoulder, a pair of clamping members disposed upon and internally bored for conforming engagement upon the tapered and reduced portions of said shank, a ring rigidly secured to one of said mem-

bers and embracing the other whereby to prevent lateral separation thereof, said members terminating in grooved jaws, the edges of said members being recessed between said ring and said jaws, and a wedge extending through said recesses and said cut away portion of the shank whereby to move said clamping members longitudinally upon said shank to cause gripping action of said jaws.

In testimony whereof I affix my signature.

ALONZO B. CLARK.
